PAGE 2

Fig. 1 is a view in perspective of a boat embodying my invention, the telescopic cabin being shown in its open position.

Fig. 2 is a view similar to Fig. 1 showing a boat embodying my invention with a telescopic cabin in its closed position.

Fig. 3 is a plan view of the boat as shown in Fig. 2.

Fig. 4 is a view in side elevation of the boat as shown in Fig. 2.

Fig. 5 is a view of the boat stern in rear elevation.

Fig. 6 is a view taken in section on the line 6-6 of Fig. 4.

Fig. 7 is a view taken in section on the line 7-7 of Fig. 4.

Each of the side seats at the rear has a patterned

center panel similar to that shown in the seat which faces rearwardly. The center seat at the rear is plain.

I claim:

The ornamental design for a boat, as shown and described.
